UNITED STATES PATENT OFFICE

JOHN Q. SHERMAN AND ALBERT W. METZNER, OF DAYTON, OHIO, ASSIGNEES, BY
DIRECT AND MESNE ASSIGNMENTS, TO THE STANDARD REGISTER COMPANY

ELECTRICAL MANIFOLDER

Application filed March 15, 1928. Serial No. 94,910.

Our invention relates to devices employed to render easy and sure of proper operation manifolding machines in which the paper feed is energized by an electric motor.

5 In United States Patent No. 1,437,949 dated Dec. 5, 1922, is described a form of operating motor, which is provided for use with our invention, and reference is made to said patent for a description of the motor, of which the 10 essential point is that when the rotor is prevented from movement, it will feed lengthwise of the stator and shut off the current.

As in said patent we provide a paper feed drive, a stop to limit the drive to single revolutions, this stop serving to open and close the 15 circuit that energizes the motor.

Also as in said patent, we operate the paper stop trip by means of a pawl which will pivot out of controlling position when the motor 20 is started, so that a single depression will always bring about the feed of but one section of paper whether the starting and release device is held down by the hand or not.

Our improvements herein deal with the 25 mode of connecting the motor to the paper feed shaft, and securing it to the machine, and also deal with a simple method whereby, should the current supply be stopped, the user may attach a handle, in a very quick and easy 30 manner, and thus operate his machine by hand.

In dealing with the motor drive for paper feeding devices of the manifolder type, there has been considerable difficulty attendant 35 upon the use of the machines of the said Letters Patent due to the fact that any inaccuracy in the paper feed shaft developed a tendency of the motor to weave about in its mountings, resulting finally in binding at its 40 connections with the machine.

In order to overcome this difficulty, we have added an improvement to the former practice as will be noted.

In connection with the shifting from motor 45 drive to hand drive for our machines, past practices required dismounting the motor, and applying a handle in the place of the motor connections. Obviously this has not been satisfactory, because current shut downs are 50 not of long duration, and a certain amount

of skill is required to mount and dismount a motor from any kind of a machine.

In our improvement we have provided for a projection of the paper feed shaft from the other side of the machine, and have covered this projection with a member which serves as a lock to hold a closed cabinet down over the frame of the machine and also when removed leaves the shaft exposed for insertion of a manual feed handle.

We accomplish the objects of our invention by that certain construction and arrangement of parts to be hereinafter more specifically pointed out and claimed.

In the drawing:

Figure 1 is a side elevation of the device.

Figure 2 is an end elevation of the frame of the machine with the motor attached, and showing a portion of the cabinet at one side and the motor drive in section.

Figure 3 is a detail of the locking bushing for the free end of the shaft.

Figure 4 is a detail of the manual feeding handle.

Figure 5 is a detail vertical section through the feed shaft of the machine on the line 5-5 of Figure 2.

Figure 6 is a perspective view of the rotor shaft of the motor.

Figure 7 is a detail showing the cabinet, 80 register frame, and feed shaft.

Figure 8 is a section illustrating the locking pins on the feed handle and plug.

The register is built on a base 1, having side frames 2, 2, which mount and journal the feed shaft 3. The feed shaft is shown as equipped with pin wheels 4 for feeding the paper, the paper storing means, writing table and method of moving the paper webs being 90 uniform with known practices, and not being illustrated.

A suitable hinging means is provided at one end of the machine for a cabinet 5, which has suitable clearance therein for the motor 95 device, and a hole 6 therein for the feed shaft at the opposite side. The cabinet is swung down so as to entirely cover the machine, and means are provided for locking it down, by the same means as plugs up the 100

hole 6. Also, through this hole the manual feed handle is inserted.

Mounted on the frame is a motor 7, like that of the patent referred to, which is released, as is the paper feed by a mechanism forming no part of this invention, but generally shown at 8.

The motor drives a gear 9, which retains some of the friction discs 10, while the shaft 10 of this gear is engaged by others of the discs. The shaft 11 (see Figure 2) is provided with a spring 12, and a nut 13 for tightening the friction is equipped at its inner end with a barrel 14 for engaging the paper feed shaft.

15 This barrel has the paper feed control cam 15 thereon, and also a grooved collar portion 16, which engages tongues on the friction discs thereby coupling them with the shaft.

20 The feed shaft is formed at the ends with slotted portions 17, terminating in holes 18, and pins 19 are set into the ends of the shaft inside of the slots, said pins forming clutch faces for driving the shaft.

25 The barrel on the gear shaft is provided with a hole 20 considerably larger than the end of the shaft, so as to permit misalignment or uneven rotation of the shaft without influencing the motor. The barrel has

30 grooves 21 at 180 degrees, for engaging the pin 19, when the barrel is thrust over the shaft. These grooves are also considerably larger than the pin, so as to drive steadily but permit freedom for uneven rotation of 35 the shaft. In order to prevent dislodgment during shipment and rough handling, we usually drive a pin 22a through the holes 22 in the barrel, which holes are larger than the pin, but which pin fits snugly in the hole 18 in the end of the groove in the feed shaft.

40 By this means the gear of the motor drives the feed shaft directly, but full allowance is made for misalignment or unevenness of motion, which is a very important factor in 45 these devices, and seriously affected the possibility of marketing them until the novel arrangement of parts now described was discovered.

The motor can be very tightly affixed to the 50 frame of the machine in view of the driving connection noted, and to this end a wide metal band 23 is provided which passes around the motor and is screwed to the side frames of the machine thereby holding the motor immovable in place.

It has been noted that the feed shaft extends out through the other side frame, from the one on which the motor is mounted. This 60 end of the shaft is the same as the end connected to the motor thus permitting a reversible shaft.

A plug 24 (Figure 3) is provided which is mounted over the end of the shaft, and has a flange 25 which lies outside of the enclosing cabinet, when the same is shut down. The

70 plug has grooves 26 which engage the clutch pin on the feed shaft, and has also a pair of spring plungers 27, which enter the holes 18 in the end of the groove in the feed shaft.

In order to place the plug on the shaft, it is thrust through the hole in the cabinet, and pushed through until it engages the shaft fully with the spring pins in place in the holes. It is then locked on the shaft and the cabinet cannot be removed, thus preventing tampering with the machine.

75 The manual feed handle has a similar barrel 28 to the plug just described, and also the handle portion 29. In the case of both the plug and the handle barrel, there is a key slot formed therein as at 30, which permits the insertion of a key to force the spring plungers outwardly, thus freeing the handle or plug.

80 When the electric current is off, the operator simply uses the key to take out the plug, replaces it with the handle, and then releases the paper feed from the motor side of the device and revolves the feed shaft by means of the handle.

85 Thus in our mechanism we provide adequately for the two problems of practical importance, still left in the electrically operated manifolder.

90 When the current is off a very quick change 95 puts a manual operating handle in place. When the feed shaft gets out of line, or revolves unevenly, or the machine frame becomes slightly distorted, still the motor will operate without tending to become loose in 100 its mounting, and a very firm method of securing it to the machine frame can be adopted.

Having thus described our invention, what 105 we claim as new and desire to secure by Letters Patent, is:—

110 In an electrically driven manifolding machine having a feed shaft therein and a motor, a loose driving connection between the motor and the feed shaft, said connection comprising pin forming projections adjacent the end of the feed shaft and a socketed element driven by the motor and arranged with notches to loosely engage said projections, 115 said socket loosely engaging over said shaft, and a second pin loosely mounted in one of the said parts and tightly engaging in the other for additionally securing the parts together against removal.

120 JOHN Q. SHERMAN.
ALBERT W. METZNER.
